UNITED STATES PATENT OFFICE

2,642,502

ROTARY SELECTOR SWITCH WITH BIAS

David W. Johnson, New Britain, Conn., assignor to The Arrow-Hart & Hegeman Electric Company, Hartford, Conn., a corporation of Connecticut

Application December 17, 1951, Serial No. 261,934

7 Claims. (Cl. 200—4)

1

This invention relates to rotary selector switches of a type that is locked in "off" position but may be unlocked and moved into an "on" or a neutral position by moving the control shaft axially and rotating it. More particularly, the invention relates to the foregoing type of switch having provision for biasing the contacts into neutral position after they have been unlocked and moved either into neutral or an "on" position.

The invention constitutes a further improvement upon or development of the invention described and illustrated in my prior Patents 2,451,224 and 2,451,225, issued on October 12, 1948. In these prior patents, the operation of the power contacts occurs when the control shaft is moved axially. In some instances this is not desirable or necessary and it is sufficient and desirable that the control shaft be biased rotatively into a neutral position from which it can be rotated at will into an "on" position without the necessity of axial movement of the shaft. Under these circumstances, it is desirable nevertheless that the switch be locked in an "off" position so that it cannot be moved therefrom without first axially moving the control shaft by a conscious and considered effort of the operator.

Therefore, it is an object of my invention to provide a rotary selector switch having a control shaft movable axially and rotatively and which is locked in one position from which it can only be unlocked by moving the control shaft axially but wherein in another rotative position, the shaft is biased but can be moved rotatively against such bias for operating selected contacts.

Other objects and advantages of the invention will appear as it is described in connection with the accompanying drawing.

In the drawing:

Fig. 1 is a side elevation view partly broken away and in section illustrating a switch embodying the principles of my invention;

Fig. 2 is a longitudinal section view taken along line 2—2 of Fig. 4 through the locking section with parts broken away;

Fig. 3 is an exploded perspective view of certain elements of the locking section;

Fig. 4 is a bottom plan view of the locking section.

Referring to the drawings, the switch is built in sections such as B and C from molded insulating base members which carry various conductive or functional parts. Operation of the device is by rotation of a shaft 20 which passes through all the sections and carries a handle 22.

2

Section B may contain wire terminals, fixed and movable contact elements and cams for operating the contacts to establish connections in control circuits for machines and electrical apparatus of any sort.

Section C may contain parts for holding the movable elements and the switch shaft in various positions into which they may be moved, and for releasably locking them in certain angular positions thereof. This section may also contain the means for biasing the switch shaft rotatively in a particular position.

The functions and the elements of the several sections are interrelated and coordinated to cause 15 the device to be locked in an "off" position, to be biased in a neutral position, and to be movable rotatively to an "on" position from the neutral position when the shaft is in one axial position and not returnable to the "off" position until 20 the handle or control shaft is moved axially.

Each of the B sections embracing the contacts and mechanism for establishing control circuits comprise a substantially square body 50 of molded insulation. The body 50 is centrally apertured 25 as at 500 to permit passage of the shaft 20 and to accommodate an operating cam member 60 that is made of molded insulating material. A square sectioned sleeve 21 is mounted on and rotates with the shaft 20 and passes through 30 the cam member which has a square opening for that purpose so that when the sleeve is rotated the cam will likewise be rotated. Each section also comprises electrical contacts such as 52, or 52', one of each pair of said contacts being spring 35 biased to engaging position and arranged to be operated by a cam member 60 to a position in which the contacts are separated. In my prior patents, the cam 60 and sleeve 21 are oriented on the shaft so that rotation of the shaft in one 40 direction will permit some contacts to engage while separating others and operation of the shaft in the opposite direction will cause a different arrangement of the closed and open contacts. In the present instance, however, one 45 preferred embodiment includes cams which will cause the contacts all to be open in the "off" position of the switch. In a neutral position, next to the "off" position, one or more of a set of contacts 52 will be closed in one of the B sections. In another of the B sections the contacts 52' will be open in neutral position but will be closed when the shaft and the control cam therewith are rotated into a position past neutral. The opening and closing of the contacts 50 in the desired positions are accomplished by cre-

55

ation of raised surfaces upon the cam members at proper places in the same manner as in my prior Patent 2,451,224.

In order to bias the control shaft in a certain axial position, a coiled compression spring 44 is wound around its reduced end 20a. One end of the spring presses against a shoulder 20b at the junction of the reduced end 20a and the main portion of the shaft while the opposite end presses upon a washer 45 of insulating material on the reduced end 20a and which in turn is pressed upon the back or bottom closure plate 47 of the switch housing. The bottom plate 47 is recessed for the passage therethrough of the reduced end 20a.

The section C comprises a square block 90 of molded insulation having a central opening for the reception of the shaft 20. At the outer end of the block 90 a handle 22 is fixed upon the end of the shaft 20. At the other end of the block 90, the central opening is enlarged for an appreciable depth providing a large chamber or recess 91. Mounted in it, is a substantially circular metal plate 88 having an opening to receive the shaft 20. Radial extensions (not visible) from the plate 88 engage in recesses in the wall of the block 90 to prevent rotation and to locate the plate at the desired point as heretofore. In order to bias the operating shaft 20 in the "off" position, there is seated on the plate 88 a spring-operating member 105 having a central opening which for part of its depth is circular as at 105a with radially extending slots 105b. For the remainder of its depth, the central opening is square in section as at 105c to receive the end of the rectangular or square sleeve 21 which operates the cams 60. Along the edge of one face, the member 105 is formed with spaced recesses as at 105d, the recesses being symmetrically disposed on opposite sides of a diameter and each being less than 180° in extent so as to provide radially extending abutments 105e at each end of the recesses. The block 90 is recessed in its end face to provide a flat face which will lie in a common plane with the face of the member 105. The block 90 is further recessed to provide recesses 99 complementary to the recesses 105d in the member 105, a recess in member 105 and a recess in the block 90 together forming a niche for the reception of a spring 107 which lies partly in each of the complementary recesses. Two springs 107 may be provided, as shown. The springs 107 are provided with flat end pieces 108 which when the switch is in normal or "off" position abut the ends of the niches. When the square sleeve 21 rotates, the member 105 and the cam 60 rotate with it as a unit. Such rotation causes the abutments 105e to engage an end of each spring and to compress the springs 107 between the abutments 105e and the ends of the recesses in the block 90. Such condition is illustrated in Fig. 4.

To prevent turning the shaft 20 from "off" position to neutral or an operating position except when it is pushed, a lock member 100 is seated in the housing 90 comprising an apertured plate stamped from sheet metal with a series of arcuate concentrically located teeth 102, 102', etc. bent to extend parallel to the axis of the shaft 20. Within and normally pressed against the bottom of the lock member 100 is a key member 96 which may be driven upon or otherwise fixedly mounted on the shaft in any suitable manner. The key member comprises a sheet metal disc having a radially extending finger 96x

which is adapted to seat within one or another of the slots 103 between the teeth 102. The spring 44 pressing upon the shaft 20 normally maintains the key member with its extension 96x located in one or another of the slots thus preventing rotation of the shaft. Upon pushing the shaft, it moves axially and carries the key member 96 and hence moves its extension 96x out from between the teeth 102', 102 permitting rotation of the shaft. Also fixedly mounted upon the shaft are stamped sheet metal members having wings 96a extending radially from the shaft in diametrically opposite positions and in register with the radial recesses 105b in the member 105. The axial pushing of the shaft carries the wings 96a into the recesses 105 so that upon rotation of the shaft the member 105 will rotate with the shaft 20 causing thereby rotation of the square sleeve and operation of the switch contact through rotation of the cam 60 as hereinbefore indicated. Rotation of the shaft in the direction of the arrow in Fig. 3 will cause movement from "off" to neutral and then to an "on" position. In the example illustrated, the tooth 102 is one half the width of the teeth 102' and 102'' on either side thereof. Thus a large notch or space 102n (equal to one half a tooth width plus a spacing 103) is provided between the tooth 102 and the tooth 102' whereas a smaller space 103 is left between the teeth 102 and 102'' such space being approximately equal to the width of the radial extension 96x. Thus, when the key member 96 has its extension removed from the notch 103 by axial movement of the switch shaft and is rotated under the large open notch 102n as the shaft is rotated and is then axially moved, the springs 107 will cause the extension 96x to press against the side of the tooth (at the right in Fig. 3). That is the neutral position of the switch. From that position, the switch can be rotated manually by turning the shaft 20 and handle 22 within the compass of the notch 102n without the necessity of axial movement of the shaft. Such movement from the neutral position in the direction of the arrow until the extension 96x abuts the tooth 102' will cause the contacts 52' to close. This is an "on" position and may also be the starting position for the switch. If the handle is now released, the switch will move back to neutral position under the bias of the springs 107. If the switch, handle and shaft furthermore are moved or pushed axially, the bias of the springs 107 and 44 will carry the parts back to "off" position wherein the extension 96x lies within the notch 103.

In order to limit the movement of the switch to the three positions just mentioned, namely "off," neutral and "on," an annular stop member 110 is provided between the locking plate 100 and the bottom of the recess 91. This stop member 110 may comprise an apertured disc with stop fingers 112 and 115 extending perpendicularly at its periphery at spaced points. The inner periphery of the stop member has a series of semi-circular indentations or recesses arranged in circular pattern to receive the shanks of one or more securing screws 113 which may be provided to hold the lock member 100 to the body 90, in any desired angular position as in my Patent 2,451,224. In assembling the device, the stop member 110 is placed with the stop finger 112 behind the locking tooth 102'' and the stop finger 115 behind the locking tooth 102'. The stop fingers 112 and 115 are higher than the lock-

ing teeth and thus the rotation of the shaft is limited by the extension 96x coming into engagement with the edges of one or another of the stop fingers 112 and 115.

Although in Fig. 3 I have illustrated a narrow tooth 192, it will be understood that this has been done mainly in order that it will not be necessary for the operator to turn the switch handle and shaft through an angle so large as would be necessary if the tooth 192 was made the same width as the teeth alongside it and the notch 102n were also made as large as a full tooth width plus two spacings 103. It will be understood moreover that the location of the raised points upon the cam surfaces of the operating cams will also be so located that the contacts they control will be caused to close at the proper times when the shaft has been rotated. In the present instance rotation through 22½° from "off" position should cause operation of the contacts 52 while rotation through a 45° angle will cause operation of both the contacts 52 and 52'.

It will furthermore be obvious to those skilled in the art that if the stop finger 115 were eliminated or located to be in back of another of the teeth on the locking member 100, the rotation of the shaft could be increased and the shaft could be held in any one of the additional positions thus provided by reason of the ability of the extension 96x to be located in another of the notches between the other teeth.

In addition to the foregoing, it should be noted that with the switch in the neutral position, i. e. with the extension 96x pressed by the springs 107 against the side of the tooth 192 in the large notch mounted 102n, the handle can be pushed or struck to move the shaft axially, whereupon the spring 107 bias will cause the switch to rotate toward "off" position. Then the spring 44 (which biases the shaft axially into the position illustrated in Figs. 1 and 2) will relocate the switch in "off" position and lock it there.

Many modifications within the scope of my invention will occur to those skilled in the art. Therefore I do not limit it to the specific form and detail of the parts.

What I claim is:

1. In an electric switch, a shaft, means for manually moving said shaft rotatively and axially, fixed means to lock said shaft against rotation when the shaft is in one axial position, positioning means fixed on the shaft and engageable with said locking means in said axial position but released from the locking means in another axial position of the shaft permitting rotation of the shaft, fixed and movable contact means, means operated by rotation of the shaft to operate said contact means selectively as said shaft is rotated into angularly spaced positions, yielding means acting to move said shaft toward a certain angular position, and means preventing return of said shaft from a second or third angular position to said certain angular position when said shaft is in said one axial position but allowing rotary movement manually between a second and a third angular position.

2. In an electric switch, a shaft, means for manually moving said shaft rotatively and axially, fixed means to lock said shaft against rotation when the shaft is in a certain axial and angular position, positioning means fixed on the shaft and engageable with said locking means in said axial position but released from the locking means in another axial position of the shaft permitting rotation of the shaft, fixed and movable contact means, means operated by rotation of the shaft to operate said contact means selectively as said shaft is rotated into angularly spaced positions and means on said locking means engaged by said positioning means in said axial position but a different angular position of said shaft preventing return rotation to said certain angular position of said shaft, and yielding means automatically rotating said shaft from a third angular position to said different angular position when freed of manual control.

3. The switch as claimed in claim 2 having yielding means normally urging said shaft into said certain axial positioning and cooperating with said first-mentioned yielding means to return said shaft to said certain axial and angular positions when the shaft is moved axially to disengage said locking and positioning means manually, without exerting rotative manual control.

4. In an electric switch, a shaft, means for manually moving said shaft rotatively and axially, fixed and movable contact means, means operated by rotation of the shaft into first, second and third positions to operate said contact means selectively, fixed means to lock said shaft against rotation when in said first position and in a certain axial position, positioning means fixed on the shaft and engageable with said locking means in said first position but movable axially to permit rotation of the shaft after said axial movement, means engaged by said positioning means to prevent rotation of the shaft between said second and said first rotative positions when in said certain axial position, but permitting rotation between said second and third rotative positions.

5. A switch as claimed in claim 4 having means to bias said shaft into said certain axial position.

6. A switch as claimed in claim 5 having means to bias said shaft into said first rotative position, whereby when moved axially from said second position, it will automatically return to said first rotative and certain axial positions.

7. A switch as claimed in claim 4 having means to bias said shaft into said first rotative position.

DAVID W. JOHNSON.
